UNITED STATES PATENT OFFICE.

PERCY W. STEPHENS, OF CHICAGO, ILLINOIS.

FUEL-RESERVE SYSTEM.

Application filed December 31, 1921. Serial No. 526,425.

To all whom it may concern:

Be it known that I, PERCY W. STEPHENS, a citizen of the United States, and a resident of Chicago, in the county of Cook and 5 State of Illinois, have invented certain new and useful Improvements in Fuel-Reserve Systems, of which the following is a specification.

The object of my invention is to provide 10 improved means whereby the driver of an automobile may receive warning that the supply of gasoline is nearing the point of exhaustion, and for withholding a reserve supply that may be drawn upon by the 15 driver after he has received such warning. My device is of the type wherein the warning is given when the level of the gasoline has reached a predetermined point, and wherein further withdrawal of gasoline is 20 permitted only when the driver manipulates the mechanism provided for that purpose. An important requirement of devices of this kind is the provision of means insuring against the mechanism being left 25 in such position that the reserve supply will be drawn off without imparting the desired warning signal to the driver. Devices of this kind have heretofore been constructed wherein automatic mechanism was provided 30 and relied upon for restoring the warning mechanism to operative position when a new supply of gasoline was taken into the tank.

Such automatic mechanism has taken different forms, generally being operatively connected to the tank filling cap or opening, whereby some operation necessary in the refilling of the tank automatically restores the warning mechanism to operative position. One of the purposes of my invention is to dispense with the mechanism necessary for automatic operation, and without such mechanism to provide with equal certainty for the restoration of the warning mechanism to operative position when a new supply of gasoline is taken into the tank. I effect this purpose by so constructing the manually operable part of the mechanism that its position indicates the operative and 45 inoperative adjustments of the warning mechanism so clearly that the tank cannot be refilled with gasoline without the operator becoming informed and reminded of the

condition of the adjustment of the warning mechanism. 55

In the drawings,

Figure 1 is a cross-sectional view of a gasoline tank with one embodiment of my invention applied thereto,

Figure 2 is a detailed view of the upper 60 end of the discharge outlet,

Figure 3 is a detailed view of the end of the operating connection, and

Figure 4 is a detailed view of another form which the free end of the operating 65 connection may take.

As illustrated, the tank 1 is provided with a filling opening, and the usual screw cap 2 for closing the same. I have illustrated my invention in connection with a 70 gravity feed system, but it will be obvious that the same principle may be applied to a vacuum or pressure feed system of the types in common use. In the application illustrated in the drawings, the gasoline is discharged from the tank 1 thru the pipe 2. The pipe 2 communicates with the interior of the tank thru the discharge member 4 to which it is attached by a coupling 5. The discharge member 4 projects thru and 75 is secured to the bottom of the tank 1.

The discharge member 4 is provided with two principal outlet ducts 5 and 6, the former communicating with the interior of the tank at a point considerably above the latter. Intermediate the level of the outlet duct 5 and the outlet duct 6 is a third outlet duct 7 which establishes communication between the interior of the tank and the duct 5 at a point slightly below the level 80 of the outlet duct 5, but sufficiently above the duct 6 to retain a sufficient reserve supply of gasoline until the valve, which controls the duct 6, is operated.

As illustrated, the member 4 consists of 95 a casting in which the outlet ducts 5 and 6 take the form of vertical channels separated by a wall 8. At some point below the inlet of duct 6 an aperture 9 is formed in the wall 8, thereby establishing communication at that point between the ducts 6 and 7. Operating in the aperture 9 is a cylindrical valve 10, the stem 11 of which projects to the exterior of the member 4 thru the housing 12 which projects therefrom. At its outer end the housing 12 is 100 105

drilled to form a working fit with the valve stem 11. At its inner end the opening in the housing 12, thru which the valve stem passes, is enlarged, as indicated at 13 to afford space for the spiral spring 14 which surrounds the valve stem, and for the packing 15 which is seated at the shoulder 16 formed at the junction of the larger and smaller parts of the bore thru the housing 12.

The outer end of the spring 14 abuts against a washer 17, which transmits the pressure of the spring to the packing 15, thereby insuring against leakage at that point, and the inner end of the spring 14 abuts against a washer 18 which is held in position on the valve stem by a pin 19 which passes thru the valve stem and against the projecting ends of which the washer 18 rests. It will be apparent that by this construction the spring 14 serves the double purpose of normally holding the valve 10 in closed position, preventing the discharge of gasoline from the duct 6 to the discharge pipe 2, and the further purpose of compressing the packing 16 to prevent leakage. Upon the valve stem 11, just beyond the end of the housing 12, I provide an annular shoulder 20, and between the inner face of the shoulder 20 and the end of the housing 12, I provide a packing washer 21. The valve 20 effects its function of closing the opening 9 by the engagement of its cylindrical surface with the walls of said opening, and hence the closure of the opening 9 is not dependent upon the valve occupying a single predetermined position, as would be the case with a cone valve resting upon a conical seat. The purpose of using this form of valve is to permit the spring 14 to force the valve inward to a position where the packing 21 will be compressed between the annular shoulder 20 and the end of the housing 12, the limits of movement necessary to effect this purpose being within the amount of movement which the valve may have while retaining the opening 9 closed. It will thus be seen that the spring 14 serves not only the two functions of closing the valve and compressing the packing 16, but also the third function of compressing the packing 21.

Attached to the valve stem 11, just outside of the end of the housing 12, is an operating member 22, preferably taking the form of a flexible cord or wire cable. This operating member 22 is of such length as to extend around the side of the tank to the filling cap 2. When no tension is exerted upon the operating member 22, the valve 10 will be held in closed position by the spring 14, and the reserve supply of gasoline below the upper outlet openings will be retained in the tank. The length of the operating member 22 is such that when it is drawn outwardly

to open the valve 10, one member of the fastening device upon the free end of the operating member is in position to engage a cooperating fastening attachment upon the filling cap 2. This fastening device may take a variety of forms. As shown in Figure 1, a stud 23 projecting upwardly from the filling cap is provided, and in the form shown in Figure 3, the end of the operating member 2 is fitted with a flat plate 24 secured to the member 22 by the tongues 25 which are integral with the flat plate, and are bent around the end part of the member 22. As shown in Figure 3, the flat plate 24 is provided with two openings 26 and 27 adapted to pass over the stud 23. When the outer opening 27 is over the stud 23, no tension is exerted upon the operating member 22, and the spring 14 operates to close and to keep closed the valve 10. When the gasoline level descends to a point below the opening 5, the operator disengages the opening 27 from the stud 23, and opens the valve 10 by pulling upon the operating member 22. The distance between the openings 26 and 27 in the fastening device is such that when the operating member is pulled outwards sufficient to open the valve 10, the aperture 26 will register with the stud 23, and may be passed thereover to hold the valve in open position while the reserve gasoline supply is being consumed. As indicated in Figure 3, the plate 24 may bear inscriptions adjacent the openings 26 and 27 indicating that when the opening 27 is in engagement with the stud 23, the spare gas valve is closed, and that when the opening 26 is in engagement with the stud 23, the spare gas valve is open.

In order to make a visual indication of the position of the spare gas valve more conspicuous, I may provide the operating member 22 with a fastening plate 28 of the form shown in Figure 4, wherein only a single aperture 29 is provided. In this form, the length of the operating member 22 is such that the aperture 29 can engage and be passed over the stud 23 only when the operating member 22 is pulled outward to open the valve 10.

For convenience, a hook 30 may be provided upon some other part of the automobile structure at such distance from the valve that when aperture 29 is passed over the hook, the valve will be permitted to close under the tension of its spring. By this arrangement when the operator refills the gasoline tank, the engagement of the fastening device 28 with the filling cap will unfailingly inform him that the reserve gasoline valve is open. While the engagement of the fastening device 28 with the stud upon the filling cap does not prevent the removal of the filling cap, and does not prevent the filling of the tank and the restoration of the

filling cap without the reserve gasoline valve being finally restored to closed position, still the attachment of the cap to the operating member 22 could not escape the operator's notice, and he thereupon would disengage the operating member from the filling cap and attach it to the hook 30; and thereby the gasoline reserve valve would be closed. The arrangement of the fastening device shown in Figure 4 and just described, is a more conspicuous reminder than the arrangement shown in Figure 3, by reason of the greater difference in position of the operating member when the reserve valve is opened and closed, respectively. The intermediate opening 7 is smaller than the outlets 5 and 6, and is designed to permit the flow of a very limited stream of gasoline after the level has descended below the outlet 5, thus insuring a period of insufficient gasoline supply to the engine just prior to the complete shutting off of the supply caused by the level of the gasoline descending to the lower edge of the opening 7. The opening 7 may either be of restricted area, or it may be partially obstructed by a covering of wire gauze as indicated at 31 in Figure 2. The purpose of the restricted intermediate outlet 7 is to cause an imperfect and halting action of the engine prior to its being completely stopped. By this means, the driver is relieved of the inconvenience of having his engine suddenly stop without warning, possibly in crowded traffic, and is enabled to draw upon his reserve supply before the motion of the car is arrested.

While I describe a specific embodiment of my invention, it will be apparent that the application of my improvement is not dependent upon the use of the particular mechanism illustrated and above described. The function of the intermediate restricted opening 7 may be effected by so forming the valve 10 and the opening 9 in which it operates that complete closure of the opening 9 is not caused by the valve. For instance if the valve were square in cross section and operating in a circular opening, a restricted flow of gasoline would be permitted from the duct 6 to the outlet pipe 2 even when the valve was in closed position. This restricted discharge would be sufficient to permit the operation of the engine, although so imperfectly as to warn the driver of the lowered level of the gasoline supply. With this construction of the valve the function of the intermediate opening 7 could be preserved and that opening dispensed with. It will also be apparent that the application of my invention is not limited to the specific location of the fastening positions of the operating means upon the filling cap and automobile structure in the precise positions illustrated and described. Both of the fastening positions might be upon an adjacent

part of the automobile structure similar to the location of the hook 30 shown in Fig. 1. The essence of this feature of my invention is that two definitely positioned fastening devices be provided for the operating means whereby the position of the operating means will afford conspicuous, definite and certain information regarding the position of the spare gasoline valve.

I claim as my invention:

1. In a device of the class described, a valve casing, a valve, a spring operative to close said valve, the stem of said valve projecting through an aperture in said casing, said spring exerting pressure upon packing material surrounding said stem at the inner and outer ends of said aperture.

2. In a device of the class described, a valve casing, a valve having a stem projecting through an opening in said casing to the exterior thereof, packing material surrounding said stem adjacent the wall of said casing on the inside and on the outside thereof, said outside packing material lying between the outer surface of said casing and a shoulder on said valve stem, a spring surrounding said valve stem inside of said casing and exerting pressure at one end to force said valve inward and to closed position and at the other end exerting pressure against said packing material on the inside of said casing.

3. In a device of the class described, a valve casing having therein two ducts and a port connecting said ducts, a valve cooperating with said port and operable through a limited range of movement to maintain said port closed, said valve having a stem projecting through an opening in said casing to the exterior thereof, packing material surrounding said stem on the inside and outside of the wall of said casing, and a spring within said casing adapted to exert pressure in one direction upon said valve and outer packing and in the opposite direction upon said inner packing.

4. In a device of the class described, a tank having a filling opening, a cover for said opening, a valve casing connected to and extending through the bottom wall of said tank, said casing having two ducts connecting with the interior of said tank at different levels, a valve-controlled port connecting said ducts, a valve having a stem projecting through an opening in said casing to the exterior thereof, packing material surrounding said stem on the inner and the outer sides of the wall of said casing, a spring within said casing and adapted to exert pressure in one direction on said valve and outer packing and in the opposite direction on said inner packing, a flexible operating member extending from said valve to the upper side of said tank, fastening mechanism comprising coacting

parts upon said cover and operating member, said parts being in cooperative relation only when said operating member is in position to hold said valve open.

5. In combination, a tank, a valve casing having a duct extending between the interior and the exterior of said tank, a valve in said duct and having a stem projecting through an opening in 10 said casing to the exterior thereof, packing material surrounding said stem upon the inside and the outside of the wall of said cas-

ing, a spring within said casing adapted to simultaneously maintain said valve in closed position and to exert pressure upon both 15 said inner and outer packing material, and adapted when said valve is forced to open position to exert increased pressure upon said inner packing material.

In witness whereof, I hereunto subscribe 20 my name this 29th day of December, A. D., 1921.

PERCY W. STEPHENS.
